(57) **CLAIM**

The ornamental design for a light up balloon string and attached weight, as shown and described.

DESCRIPTION

FIG. 1 is a perspective view of a light up balloon string and attached weight showing our new design;

FIG. 2 is a front elevational view of an enlarged detail view thereof;

FIG. 3 is a bottom plan view of FIG. 2;

FIG. 4 is a rear elevational view of FIG. 2;

FIG. 5 is a front elevational view of FIG. 2;

FIG. 6 is a right side elevational view of FIG. 2; and,

FIG. 7 is a left side elevational view of FIG. 2.

The balloon depicted by broken lines in FIG. 1 has been shown for illustrating environment that forms no part of the claimed design.
